[57] CLAIM

The ornamental design for a braking force indicator, as shown and described.

DESCRIPTION

FIG. 1 is a perspective view of a braking force indicator showing my new design, with the wires broken away to indicate indeterminate length;

FIG. 2 is a front view thereof;

FIG. 3 is a rear view thereof;

FIG. 4 is a top view thereof;

FIG. 5 is a bottom view thereof;

FIG. 6 is a right end view thereof; and,

FIG. 7 is a left end view thereof.
